UNITED STATES PATENT OFFICE.

GEORGE KNIGHT, OF BROCKTON, MASSACHUSETTS.

MARKING-MACHINE.

1,254,704.

Specification of Letters Patent. Patented Jan. 29, 1918.

Application filed January 25, 1915. Serial No. 4,101.

To all whom it may concern:

Be it known that I, GEORGE KNIGHT, a citizen of the United States, residing at Brockton, county of Plymouth, State of Massachusetts, have invented an Improvement in Marking-Machines, of which the following description, in connection with the accompanying drawing, is a specification, like characters on the drawing representing like parts.

This invention relates to marking machines of that type that are used for marking or printing trade names, manufacturers' names, or other identifying data on cloth, leather, or other similar material. Machines of this type are used to some extent in the manufacture of shoes for marking identifying data on different parts of the shoe, or for marking the name of the manufacturer or trade name on the inside facing or some other part of the shoe. Machines of this character are also used in various other lines of manufacture for somewhat similar purposes. Such machines generally include a printing couple comprising a platen, on which the work is placed, and a die member or impression member carrying type characters, which die member is movable toward and from the platen thereby to make the printed impression.

In some machines of this character the impression-making compound or material is in the form of gold leaf or other metal leaf carried by a backing in the form of a strip or sheet, and the device herein illustrated is of this type. One of the objects of my invention is to provide novel means for feeding the strip carrying the gold leaf as successive impressions are made, so that each impression will be made from a fresh portion of the strip.

In some classes of work it is desirable that the printing member should remain in contact with the work for a considerable length of time in order to make a proper impression, and one feature of my invention relates to a means by which there will be a dwell or pause in the movement of the die member when it is in contact with the work. In order to give an understanding of my invention I have illustrated in the drawings a selected embodiment thereof which will now be described, after which the novel features will be pointed out in the appended claims.

Referring to the drawings Figure 1 is a side view of a machine embodying my invention;

Fig. 2 is a front view thereof;

Fig. 3 is a side view showing the side opposite to that shown in Fig. 1;

Fig. 4 is a detail view showing the part of the control mechanism by which the plunger is caused to dwell when in contact with the work;

Fig. 5 is a fragmentary sectional view showing the strip-feeding means;

Fig. 6 is a section on the line *x*—*x*, Fig. 4;

Fig. 7 is a section on the line *y*—*y*, Fig. 6;

Fig. 8 is a detail view of the clutch mechanism, being a section on the line *a*—*a*, Fig. 9;

Fig. 9 is a section on the line *b*—*b*, Fig. 8;

Fig. 10 is a section on the line *c*—*c*, Fig. 1;

Fig. 11 is a perspective view of the pawl releasing member 86;

Fig. 12 is a section on the line *d*—*d*, Fig. 5;

Fig. 13 is a plan view of the platen showing the gage.

The elements of the printing couple are indicated at 1 and 2, respectively, 1 being the platen on which the work is supported, and 2 being the die or impression member. The platen is herein shown as sustained by a suitable frame 3 which also supports the operative parts of the machine, this frame being herein shown as constructed to be secured to a bench or bed 4. The die member 2 is carried by a plunger 5 which is movable toward and from the platen 1 and is mounted in suitable guides or ways 6 formed on the frame 3. This plunger may be given its reciprocating movement in any suitable way and in the construction shown I have provided means for actuating it from a driving shaft 7 which is mounted in suitable bearings formed on the frame and is driven from a driving pulley 8 through suitable clutch mechanism presently to be described. This shaft 7 is shown as provided with an eccentric 9 which is connected to the plunger through a connecting rod 10 so that rotation of the shaft will give the plunger its reciprocating movement. I will preferably make the die member 2 carrying the type characters so that it can be removed from the plunger thereby enabling me to employ any one of a number of die members, according to the character of the

65

70

105

110

data which it is desired to print on the work. The die member may be secured to the plunger in various ways without departing from my invention. In the illustrated embodiment said member 2 is clamped between two clamping jaws 11 which are operated by the clamping screw 12 carried by the plunger and having right and left-hand screw-threaded portions that engage the two jaws 11, respectively. One end of this screw 12 projects beyond the plunger, as shown at 13, and said end is shaped to receive a wrench, key or other tool by which the screw may be turned.

15 The platen member 1 will preferably be provided with a suitable gage by which the work 14 can be properly positioned. The gage herein shown comprises two gaging fingers 15 situated at opposite sides of the 20 platen 1 and against which the edge of the work 14 may be placed. I will preferably provide means for adjusting this gage so that the printed impression may be placed at any desired distance from the edge of the work. In the illustrated embodiment 25 of my invention this is provided for by mounting the fingers 15 on a plate or member 16 that is situated at the back of the platen 1 and which is provided with a stem 17 extending into an opening in the platen and having at its front end a screw-threaded bore 18 into which an adjusting screw 19 is screw-threaded, the head of the adjusting screw being accessible from the front of the 30 platen. The opening in the platen through which the stem 17 extends is enlarged at its rear end, and a spring 20 is situated in said enlarged portion, said spring encircling the stem and bearing at one end against the member 16 and at the other end against a shoulder 21. The spring tends normally to 35 force the gage rearwardly, while the adjusting screw 19 retains the gage in its adjusted position. By backing the screw 19 off, the spring 20 will force the gage rearwardly and by turning the screw up the gage will be drawn forwardly.

40 As stated above, one of the objects of my invention is to provide a novel machine of this class which embodies means for feeding a strip containing some printing material between the work and the die 2, so that when the die descends and is brought into printing position, the type characters thereon will engage the strip and cause a transfer 45 of the printing material on the strip to the work 14. While the strip may contain any printing material the machine herein shown is especially useful where the strip is coated with gold leaf, so that the operation of the die 2 will be to transfer the gold leaf from the portion of the strip with which the type characters engage to the work, thus making a gold impression on the work. The strip 50 is shown at 22 and it may be formed of

paper, cloth or any material which can be loaded with printing compound. This strip is fed to the work through a strip-guiding member 23 secured to the front of the machine and comprising a support or plate 24 70 on which the strip rests, and guiding flanges 25 that overlie the edges of the strip and hold it in position. The strip 22 may be in the form of a continuous strip, in which case it will be taken from a roll or other 75 source of supply, or it may be formed in comparatively short lengths, or in pieces of sufficient length to be fed into the top of the guide 23 as occasion requires. The lower end 26 of the guide 23 is situated 80 slightly above the platen, as shown best in Figs. 1 and 5, said guide having the curved delivery apron 27 over which the strip passes. From this delivery apron the strip feeds across the platen above the work 14 85 and extends to a strip-feeding mechanism designed to feed the strip forward, one step at each operation of the machine. Any suitable strip-feeding mechanism may be provided without departing from the invention. In the construction herein shown 90 said strip-feeding mechanism comprises a reciprocating feeding element for gripping the strip and feeding it forward, and a retaining element to engage the strip and prevent backward movement thereof when the feeding element is moving backward to secure a fresh grip on the strip. The feeding element comprises the two gripping jaws 28 95 and 29, the jaw 28 being shown as constituted by the bridge portion of a yoke-shaped member 30 between the arms of which the strip 22 extends, said arms being pivoted to the frame at 230. The other gripping member 29 is shown as constituted by the lower edge 100 of a plate or bar 31 which extends from one arm to the other of the yoke-shaped member 30 and is pivotally mounted in said arms at 32. When the member 31 is in the full line position Fig. 5, the gripping jaws are 105 open which is the position when said gripping element is moving forwardly in the direction of the arrow *o* into the dotted line position to get a fresh grip on the strip. When the bar 31 is moved into the dotted 110 line position, Fig. 5, and starts its return movement, the lower edge thereof will grip the strip between itself and the member 28, and this is the position of the parts during 115 the strip-feeding movement in the direction 120 of the arrow *p*.

I have provided herein means for giving the yoke 30 its reciprocating movement, which means also operates to swing the bar 31 into its gripping position when the yoke 125 30 is given its strip-feeding movement, and into its non-gripping position when said yoke is moved forwardly. This means comprises a link 33 pivotally connected to the bar 31 at 34 below the pivotal connection 32 130

of the bar with the yoke 30. The link 33 is pivotally connected at 35 to the lower end of an arm 36 which is fast on a rock-shaft 37 mounted in the frame of the machine. 5 This rock-shaft has an arm 38 fast thereon to which is connected a link or connecting rod 39 that is actuated by an eccentric or crank 40 on the shaft 7, said eccentric being properly timed and positioned to give the 10 arm 36 its requisite movement. The connection between the link 39 and the arm 38 is adjustable so as to provide for giving a greater or less feeding movement to the strip at each reciprocation. This adjustment is 15 herein provided for by making the arm 38 with the slot 41 in which is adjustably mounted a bolt 42 by which the link 39 is connected to the arm 38. The strip-retaining element which holds the strip against 20 backward movement when the gripping element is moving from the full to the dotted line position Fig. 5 is herein constituted by a rest 43 over which the strip 22 passes and which is sustained by an arm 44 secured to 25 the frame, and a clamping member 45 movable toward and from the rest, said clamping member being operative to clamp the strip against the rest when the feeding element is moving forwardly and being separated from 30 the rest when the feeding element is giving the strip its feeding movement. This clamping member 45 is carried by an arm or plate 46 which is pivotally connected at 47 to the end of an arm or support 48 secured 35 to the frame. The member 46 has extending upwardly therefrom a flange or ear 49 which overlies one side of the link 33 and is frictionally held thereagainst by a screw 50 that is screw-threaded into the ear 49 and extends 40 through a slot 51 in said link, a resilient washer 90 being confined between the head of the screw and the link. This construction provides a frictional connection between the link and the clamping member by which the 45 reciprocating movement of the link gives the required movement to the said clamping member to clamp and unclamp the strip. When the link 33 moves to the left Fig. 5, as shown by the arrow *o*, the friction of the 50 link against the ear 49 and spring member 90 will cause the member 46 to turn about its pivot to bring the clamping member 45 against the strip thereby clamping the latter against the rest 43. The screw 50 will be 55 adjusted so that while the friction developed is sufficient to rock the member 46, yet it will permit the link to continue its movement after the clamping member has been brought against the rest, and during this continued 60 movement the friction holds the clamping member in its strip-clamping position. When the link 33 moves backwardly or in the direction of the arrow *p*, to give the member 28 its strip-feeding movement, the friction between said link and the member 65

46 turns said member into the dotted line position to release the clamping pressure on the strip thereby to allow the strip to move forwardly freely. It will thus be seen that I have provided a friction device for actuating the clamping member 45, which friction device is operated by the means for actuating the gripping member. 70

In operating with some kinds of printing material a better impression can be made if 75 the die or platen is heated. I have, therefore provided means for heating the die, this being herein accomplished by forming the plunger with an aperture or opening 52 into which a heating element, such, for instance, 80 as an electric heater, can be inserted for maintaining the die in a heated condition.

In making some kinds of printed impressions it is desirable that the die should remain in contact with the work or with the 85 strip 2 for an appreciable length of time, and one feature of my invention relates to a construction by which the time interval during which the die is in contact with the work may be increased or diminished. When the 90 shaft 7 is rotating at a uniform speed, the time interval during which the die is in contact with the work or strip is comparatively short, as this contact will occur only when the eccentric is passing its dead center. In machines of this nature where a longer contact is desirable, it has been heretofore necessary to hold the work in position while the die made several successive reciprocations in order to make a good impression. My invention provides means 95 whereby the die 2 may be brought to rest when in contact with the work or with the strip, that is, in printing position, and remain at rest for a predetermined length of 100 time, and then be carried into the position shown in Fig. 1. In machines of this type, it is customary to employ a so-called one-revolution clutch between the driving pulley and the operating shaft so that the machine 105 will be brought to rest with the die in raised position after one cycle of operation. I have provided herein means whereby the clutch may be disengaged when the plunger is in its lowered or printing position and engaged again after a predetermined time interval thereby to complete the cycle of operations and raise the plunger. The clutch herein shown comprises a clutch member 53 in which is slidably mounted a clutch dog 110 115 54 that is adapted to engage a shoulder or projection formed on the driving pulley 8 when said dog is in its operative position. This clutch dog is acted upon by a spring 56 which tends normally to throw it into its 120 operative position, as shown in dotted lines Fig. 9, and is also provided with a laterally-extending releasing finger 55 with which a releasing member or knock-off 57 is adapted to engage, the latter having a beveled face 130

58. The releasing finger 57 is carried by a lever 59 pivotally mounted at 60, said lever having a laterally-extended portion 61 to which is connected a link 62 leading to a treadle or other actuator. This arm is acted upon by a spring 63 which tends normally to hold it in operative position with the member 57 in position to engage the finger 55. To start the machine the connection 62 is drawn downwardly by a treadle or other device thereby rocking the arm 59 into the dotted line position Fig. 1 and removing the releasing member 57 from engagement with the finger 55. This allows the spring 56 to move the clutch dog 54 into clutching engagement with the driving pulley 8 thereby starting the machine in operation. If after the machine is started, the treadle is released the lever 59 and member 57 will assume the full line positions Figs. 1 and 8, and when the shaft 7 completes its revolution, the finger 55 will engage the bevel portion 58 of the releasing member and thereby be moved backwardly into the full line position Fig. 9 and disengaged from the driving pulley.

The above describes a more or less familiar construction of one-revolution clutch. In addition I have provided herein a device which can be thrown into and out of operative position as desired and which when in operative position operates to disengage the clutch when the plunger is in its printing position and to hold said clutch disengaged for a predetermined length of time and then to automatically cause the clutch to be re-engaged again to bring the plunger back into its elevated position. This device comprises an auxiliary clutch-releasing member 64 which can be moved into position to engage the clutch-releasing finger 55 or out of such position. This auxiliary clutch-releasing member 64 is so situated that when it is in its operative position it will engage the finger 55 and release the clutch when the plunger is in its lowered or printing position. This releasing member 64 is carried by a member or lever 65 pivotally mounted at 66 upon a carrier 67 adapted for vertical movement on the frame 3 so that when the carrier 67 is in its elevated position the releasing member 64 will be in its operative position, while when the carrier is in its lowered position the releasing member 64 will be inoperative. This carrier is shown as provided at its upper end with a slot 68 embracing a stud 69 carried by the frame and is provided at its lower end with another slot 70 through which a clamping screw 71 extends. This screw and stud guide the carrier in its vertical movement and the clamping screw 71 serves to hold it in its elevated position. The carrier 67 sustains a shaft 74 carrying a gear 72 which when the carrier is raised is adapted to mesh

with a gear 73 rigid with the driving pulley 8. The shaft 74 is also provided with a pinion 75 that meshes with a gear 76 mounted on the carrier, and said gear actuates a cam member 77 adapted to engage the lower end 80 of the lever 65 thereby to move the disengaging member 64 into its initial position. The gearing 72, 75, 76 is thus driven from the driving pulley 8 so that when the carrier 67 is in its elevated position said gearing is operating continuously. When, therefore, the carrier 67 is in its elevated operative position with the gear 72 in mesh with the gear 73 and the machine is started in operation by releasing the clutch the shaft 7 will make a half revolution to bring the die member 2 into its lowered printing position, at which time the clutch will be disengaged by the member 64, allowing the die member to remain in its lowered position. The continued rotation of the driving pulley 8 and gear 73 will operate the train of gearing 72, 75, 76 and thereby rotate the cam 77, and when said cam has been turned sufficiently to bring the projection 81 thereon against the roll at the lower end of the lever 65, said lever will be turned about its pivot to throw the disengaging member 64 out of engagement with the releasing finger 55 thereby permitting the clutch to become engaged again. The shaft 7 will then be rotated further until the clutch is disengaged by the member 57 when the plunger is elevated.

I have also provided means whereby the length of the time interval during which the plunger will remain in printing position can be varied. I accomplish this herein by providing means whereby the cam 81 can be adjusted so that it will occupy different positions when the machine is brought to rest with the plunger elevated. This cam 77 is adjustably mounted on a bushing 82 that in turn is rotatably mounted on a sleeve 99 fast to a shaft 98 to which the gear 76 is secured. The sleeve 99 is provided with ratchet teeth 83 and the bushing 82 has integral therewith a housing 96 in which is retained a spring-pressed pawl 84 that is adapted to engage the ratchet teeth 83 whereby the cam will be rotated forwardly by the shaft 98. This pawl is provided with a laterally-extending finger 85 which is adapted to be engaged by a pawl-lifting member 86 that is slidably mounted in the bearing 87 for the shaft and is acted upon by a spring 88 that normally tends to throw it into its operative position. A cam member 89 is slidably mounted in the bearing 87 and is provided with a cam face 90 adapted to engage a correspondingly-shaped face on the pawl-releasing member 86. This member 89 is acted upon by a suitable spring 91 which tends normally to hold it in inoperative position. When the carrier 67 is ele-

vated the actuating member 89 stands in line with a projection 92 formed on the clutch lever 59 so that when the treadle 62 is depressed and the lever 57 is moved to disengage the clutch, the projection 92 will engage the member 89 and move it into a position to withdraw the member 86 from the pin 85. This permits the pawl 84 to move into its operative position in engagement 10 with the ratchet 83 thereby coupling the cam to the shaft 98. The cam will, therefore, be set in rotation and will continue to rotate with the shaft 98 until the latter has made one complete rotation, when the finger 15 85 will ride up the inclined portion 175 of the pawl-disengaging member 86 thereby lifting the pawl out of operative engagement with the ratchet 83. The parts will remain in this position until the clutch is operated to set the machine in operation again. 20

The cam 77 is secured in its adjusted position on the sleeve 82 by means of a set-screw 910, which set-screw provides for shifting the position of the cam relative to the sleeve 82. This adjustment of the cam 77 provides for varying the time interval during which the die member will be in contact with the work or in printing position. When the cam 77 is so adjusted on the sleeve 30 82 that it will occupy the position shown in Fig. 1 when the parts come to rest, then said time interval will be the greatest, for the parts will remain in printing position during substantially a complete rotation of the 35 cam. If a shorter time interval is desired the cam 77 will be adjusted on the sleeve 82 to set the projection 81 into a position so that it will engage the roll 80 before it makes a complete revolution, such adjustment of the cam 77 shortening said time interval. By this means it is possible to regulate the time interval that the die member is in printing contact with the work so as to produce the desired results. The construction above described is especially useful where it is desired to emboss the material or to form a burnt impression therein, for by heating the die and then causing the die member to dwell for a desired length of 45 time when in printed engagement with the work, said die member will burn an impression in the work.

In the above application I have used the term "strip" as indicating the sheet or vehicle which carries the printing compound, whether the latter be ink or gold leaf, or any other material. This so-called strip may be in comparatively short pieces or may have a long ribbon-like shape, and I have used the term "strip" in the claims not with the intention of describing a limitation of the vehicle carrying the inking compound, but merely as a convenient term for indicating some such vehicle.

65 In order to provide for operating equally

well on work of varying thicknesses, I have provided means for adjusting the plunger 5 relative to its operating mechanism. I have arranged for this herein by providing an adjustable connection between the connecting rod 10 and said plunger 5, said connection being best seen in Fig. 10. The connecting rod is pivotally connected at its lower end on a pivotal pin 143, the central portion 144 of which to which the connecting rod 10 is secured being eccentric slightly relative to the ends 145. The eccentric ends of this pin are journaled in bushings 146 carried by the plunger, and one end of the pin is provided with a tool-receiving socket 80 into which a tool 147 may be inserted through an opening 148 in the guideway 6. By turning the pin 143 the plunger will be adjusted relative to the connecting rod due to the eccentricity of the ends 145 of said pin. This adjustment is sufficient to compensate for different thicknesses of material. 85

While I have illustrated herein a selected embodiment of my invention I do not wish to be limited to the constructional features 90 shown.

I claim:

1. In a device of the class described, the combination with a platen, of a die member movable toward and from the platen, means to feed a strip carrying printing material between the die member and platen, said means comprising a pivotally-mounted yoke-shaped member, a strip-gripping bar pivotally sustained by said member, a vibrating actuating arm connected to said strip-gripping bar and by which the yoke member is oscillated, movement of said arm in one direction causing the bar to grip the strip and giving the feeding device its feeding movement, and movement in the opposite direction releasing the bar from the strip and giving the feeding device its return movement. 100

2. In a device of the class described, the combination with a platen, of a die member movable toward and from the platen, means to feed a strip carrying printing material between the die member and platen, said means comprising a pivotally-mounted yoke-shaped member, a strip-gripping bar pivotally sustained by said member, a vibrating actuating arm connected to said strip-gripping bar and by which the yoke member is oscillated, movement of said arm in one direction causing the bar to grip the strip and giving the feeding device its feeding movement and movement in the opposite direction releasing the bar from the strip and giving the feeding device its return movement, and a strip-clamping device operable to clamp the strip during the return movement of the feeding device. 115

3. In a device of the class described, the combination with a platen, of a die mem- 120

- ber movable toward and from the platen, means to feed a strip carrying printing material between the die member and platen, said means comprising a pivotally-mounted 5 yoke-shaped member, a strip-gripping bar pivotally sustained by said member, a vibrating actuating arm connected to said strip-gripping bar and by which the yoke member is oscillated, movement of said arm 10 in one direction causing the bar to grip the strip and giving the feeding device its feeding movement and movement in the opposite direction releasing the bar from the strip and giving the feeding device its return movement, and a strip-clamping device 15 operated by the actuating arm to clamp the strip during the return movement of the feeding device and to release the strip during the feeding movement thereof.
- 20 4. In a marking machine, the combination with a platen, of a die member, means to give the die member and platen a relative movement toward and from each other, a feeding device for feeding a strip carrying 25 printing material between the die member and platen, said device comprising a pivotally-mounted yoke-shaped member, a strip-gripping bar pivoted to said member, a vibrating actuating arm and a link connecting 30 said arm and bar whereby movement of the link in one direction causes the bar to grip the strip and gives the yoke-shaped member a strip-feeding movement, while movement of the link in the opposite 35 direction releases the gripping bar and gives the yoke-shaped member its return movement.
3. In a marking machine, the combination 40 with a platen, of a die member, means to give the die member and platen a relative movement toward and from each other, a feeding device for feeding a strip carrying printing material between the die member and platen, said device comprising a 45 pivotally-mounted yoke-shaped member, a strip-gripping bar pivoted to said member, a vibrating actuating arm and a link connecting 50 said arm and bar whereby movement of the link in one direction causes the bar to grip the strip and gives the yoke-shaped member a strip-feeding movement, while movement of the link in the opposite 55 direction releases the gripping bar and gives the yoke-shaped member its return movement, and a strip-clamping device rendered operative by the movement of the link to clamp the strip and prevent return movement of the feeding device.
6. In a device of the class described, the 60 combination with a platen, of a plunger, means to move the plunger toward and from the platen, a die member carried by the plunger, a reciprocating strip-feeding device having means to grip the strip intermittently and feed it forward, strip-

clamping means to prevent return movement of the strip, and a frictional connection between said strip-feeding means and said strip-clamping means whereby the latter is operated by the former.

7. In a device of the class described, the combination with a platen, of a plunger movable toward and from the platen, a die member carried by the plunger, a strip-gripping device, means to reciprocate it and cause it to grip a strip while moving in one direction and to release a strip when moving in the opposite direction whereby a strip carrying printing material is fed intermittently between the die member and platen, strip-clamping means, and a frictional connection between said strip-gripping device and strip-clamping means whereby the latter is actuated by the former to clamp the strip during the return movement of the strip-gripping device.

8. In a device of the class described, the combination with a platen, of a plunger movable toward and from the platen, a die member carried by the plunger, a strip-feeding device comprising a pivotally-mounted yoke and a strip-gripping member pivoted thereto, means to vibrate said yoke and member and thereby feed intermittently a strip carrying printing material between the die member and platen, a strip-clamping device, and a frictional connection between said strip-clamping device and said vibrating means whereby the latter is actuated by the former.

9. In a device of the class described, the combination with a frame, of a platen sustained thereby, a plunger movable on the frame toward and from the platen, a die member carried by the plunger, a driving element for reciprocating the plunger, a clutch for operatively connecting the driving element to the plunger, a carrier movably mounted on the frame, means mounted on the carrier for automatically disengaging the clutch and for causing the clutch to become operative again, means for holding said carrier in either its operative or inoperative position on the frame, and means connecting the mechanism on the carrier with the driving element when said carrier is in its operative position.

10. In a device of the class described, the combination with a frame, of a platen sustained thereby, a reciprocating plunger mounted on the frame, a die member carried by the plunger, a driving element for reciprocating the plunger, a clutch forming an operative connection between the driving element and plunger, a carrier movably mounted on the frame and adapted to be placed in either operative or inoperative position, clutch-disengaging means on said carrier which is in operative position to disengage the clutch when the carrier is in

operative position but which in inoperative to disengage the clutch when the carrier is in inoperative position.

11. In a device of the class described, the combination with a frame, of a platen sustained thereby, a reciprocating plunger mounted on the frame, a die member carried by the plunger, a driving element for reciprocating the plunger, a clutch forming an operative connection between the driving element and plunger, a carrier movably mounted on the frame and adapted to be placed in either operative or inoperative position, clutch-disengaging means on said carrier which when the carrier is in operative position is situated to disengage the clutch at the time that the die member is in printing position, said clutch-disengaging means being inoperative to disengage the clutch when the carrier is in inoperative position.

12. In a device of the class described, the combination with a frame, of a platen sustained thereby, a reciprocating plunger mounted on the frame, a die member carried by the plunger, a driving element for reciprocating the plunger, a clutch forming an operative connection between the driving element and plunger, a carrier movably mounted on the frame and adapted to be placed in either operative or inoperative position, clutch-disengaging means on said carrier which when the carrier is in operative position is situated to disengage the clutch at the time that the die member is in printing position, said clutch-disengaging means being inoperative to disengage the clutch when the carrier is in inoperative po-

sition, and means on said carrier to cause the clutch to be operative again after a predetermined time interval. 40

13. In a device of the class described, the combination with a platen, of a plunger movable toward and from the platen, a die member carried by the plunger, a shaft by 45 which said plunger is operated, a driving element, a clutch for connecting said driving element to said shaft, and means automatically to disengage said clutch when the die member is in printing position and to 50 render said clutch operative again after a predetermined time interval, said means being shiftable into or out of operative position.

14. In a device of the class described, the combination with a platen, of a plunger movable toward and from the platen, a die member carried by the plunger, a shaft by 55 which said plunger is operated, a driving element, a clutch for connecting said driving element to said shaft, means automatically to disengage said clutch when the die member is in printing position, and means actuated by the driving element to render 60 said clutch operative again after a predetermined time interval, said last-named means being shiftable into operative or inoperative connection with the driving element. 65

In testimony whereof, I have signed my 70 name to this specification, in the presence of two subscribing witnesses.

GEORGE KNIGHT.

Witnesses:

LOUIS C. SMITH,
BERTHA F. HEUSER.
